Primary Examiner — Holly Baynham*Assistant Examiner* — Rhea Shields(74) *Attorney, Agent, or Firm* — Panitch Schwarze Belisario & Nadel LLP(57) **CLAIM**

The ornamental design for a drug vial adapter with downwardly depending stopper, as shown and described.

DESCRIPTION

FIG. 1 is a perspective view of a drug vial adapter with downwardly depending stopper in accordance with a preferred embodiment of my new design;
 FIG. 2 is a front elevation view thereof;
 FIG. 3 is a right side elevation view thereof;
 FIG. 4 is a rear elevation view thereof;
 FIG. 5 is a left side elevation view thereof;
 FIG. 6 is a top plan view thereof; and,
 FIG. 7 is a bottom plan view thereof.
